DESIGN FOR A CONDIMENT DISPENSER

Chester A. Kurrash, Detroit, Mich.

Application November 8, 1946, Serial No. 134,637

Term of patent 14 years

(Cl. D44—22)

To all whom it may concern:

Be it known that I, Chester A. Kurrash, a citizen of the United States, residing at Detroit, in the county of Wayne and State of Michigan, have invented a new, original, and ornamental Design for a Condiment Dispenser, of which the following is a specification, reference being had to the accompanying drawing, forming a part thereof.

Fig. 1 is an elevational view of a condiment dispenser showing my new design.

Fig. 2 is an additional elevational view thereof showing the portions of the condiment dispenser disclosed in Fig. 1 in separated position.

I claim:

The ornamental design for a condiment dispenser, as shown.

CHESTER A. KURRASH.
